UNITED STATES PATENT OFFICE.

BENJAMIN SOETERS, OF THE HAGUE, NETHERLANDS.

THERMOSTATIC CIRCUIT CLOSER.

Application filed May 5, 1921. Serial No. 467,194.

To all whom it may concern:

Be it known that I, BENJAMIN SOETERS, a citizen of the Kingdom of the Netherlands, residing at The Hague, Kingdom of the Netherlands, Ten Hovestraat 68, have invented certain new and useful Improvements in Thermostatic Circuit Closers, of which the following is a specification.

The object of my invention consists in improvements in such devices for producing audible or visible signals, with which the said signals are obtained by interrupting a main circuit and closing a relay circuit, in which relay circuit the means for producing 15 the audible or visible signals are inserted.

The feature of my invention consists therein that the fusion of an interrupter, inserted between two adjacent ends of an electrical wires, subdivided at certain distances, 20 is used to produce the said interruption of the main current and the closing of the relay current, wherein the means for emanating audible or visible signals are inserted.

The fusion of said interrupter is attained 25 by employing easily fusible metal or other suitable material, suitable to conduct electric current, to which interrupter pieces of easily inflammable material are attached or otherwise fixed.

The subdivision of the main current wire 30 and the insertion of interrupters between two adjacent ends of said wire so produced, may be effected at any convenient place of said main circuit, and as many times as 35 spaces, rooms or other places should be protected or secured against fire.

In the practical execution of my invention, as the easily fusible material for connecting two adjacent ends of the main circuit at the points of subdivision, tin-foil lamina of suitable size and thickness may be employed and as easy inflammable material, which may be fastened or otherwise attached to said interrupter, paper, tissue paper, silk 45 gauze, silk tissue or the like may be used.

In the accompanying drawing several forms of execution of my invention are diagrammatically illustrated.

Fig. 1 represents a form of execution of 50 my invention, wherein one wire is used only, showing an interrupter inserted between two adjacent ends of said wire, at the point of subdivision of same.

Fig. 2 shows another form of execution,

wherein special contact pieces are used for 55 the formation of the relay circuit, in addition to the wires of the main current.

Fig. 3 represents another method of execution, wherein the means for conducting the electric current, are disposed on two cylinders concentrically arranged with regards to, and movable in, each other.

Fig. 4 shows a fourth mode of execution, wherein spring contacts are provided which act against the conducting wire of the main 65 circuit.

Figure 5 is a substantially transverse sectional view taken on the lines 5—5 of Figure 2.

In the form of execution of my invention, 70 as represented in Figs. 2 and 3, the electric connection is produced by contact surfaces of tin-foil lamina or of any other suitable conducting material, with the wires of the main circuit. Also the connection of two 75 adjacent ends of the wire of the main circuit is effected by tin-foil lamina, or by any other suitable, easily fusible material.

The closing of the main circuit is effected 80 by connecting the ends of the wire of the main current with said contact surfaces. The metallic contact of the ends of the subdivided wire is also with this method of execution effected by inserting an easy fusible thin metal sheet or thin lamina, to which 85 metal lamina the said easily inflammable paper or gauze or tissue is attached.

It results from the foregoing that in order 90 to keep the relay circuit open, the main circuit must be closed, and this is effected by causing the electric current to pass through the subdivided wire of the main circuit, whilst the adjacent edges of same being connected by the said lamina of easy fusible metal.

In the drawings Fig. 1 represent 1, 1 the 95 conducting wire of the main circuit; 2, 2 the adjacent edges of same at the place of subdivision of same; 3 the lamina or connecting bridge of easy fusible material. To the said lamina, the easy inflammable material 4 as paper, tissue paper, silk gauze, silk tissue and the like is fixed.

With the form of execution according to 100 Fig. 2, 1, 1 designate the conducting wire of the main circuit; 5, 5 the conducting connecting surfaces, for instance thin metal sheets, or tin-foil lamina, the same being

connected by the interrupter or bridge 3 with the edges of the conducting wire at the places of subdivision.

In Fig. 3, 6 and 7 designate two concentric bodies, for instance cylinders or prisms, the external one 7 of which is supported by and embraces the wires 1, 1 while the internal one 6 is provided with the contact pieces 5, 5 on opposite outsides thereof. The interrupter of fusible material 3 is carried by the internal cylinder 6, the said cylinders or prisms being telescopically movable relative to each other. The internal one 6 may be made either hollow or as a solid body. The purpose of this telescopic construction is to facilitate the insertion of new cylinders 6 into position, and to protect the electrical contacts made between the wires 1 and the contact surfaces 5.

This apparatus may also be executed as shown in Fig. 4, by disposing a spring contact 8, which acts against the wire 1, 1.

As an advantage of the apparatus according to my invention, there may be mentioned that due to small costs connected with its manufacturing, the same may be applied largely for improving security against fire.

The method of operation of my apparatus is the following:

In case of fire, by the ignition of the easy inflammable material 4, the said interrupter

3 of easy fusible material is caused to fuse. I claim:

1. A thermostatic circuit closer comprising parallel auxiliary circuit wires, a body portion having contact surfaces on opposite sides thereof and being removably and frictionally supported between and by said wires to allow contact between each of said wires and one of the contact surfaces, a fusible circuit-section carried by said body portion and connecting said contact surfaces and a hollow cylinder supported by and embracing the circuit wires. 35 40

2. A thermostatic circuit closer comprising parallel auxiliary circuit wires, a hollow cylindrical member supported by and embracing the wires, a cylindrical body portion having contact surfaces on opposite outsides thereof and telescopically removably frictionally supported between said wires to allow contact between each of said wires and one of the contact surfaces, and a fusible circuit-section carried by said body portion and electrically connecting said contact surfaces. 45 50

3. In a thermostatic circuit closer, the combination with the elements claimed in claim 2 of inflammable material suspended on the fusible circuit-section. 55

In testimony whereof I affix my signature.

BENJAMIN SOETERS.
